UNITED STATES PATENT OFFICE.

WALTER C. GHETTI, OF SAN JOSE, CALIFORNIA.

ANCHOR.

Application filed November 30, 1925. Serial No. 72,371.

This invention relates particularly to an anchor for use in securing a plate, or any other desired article to a marble slab or block, or for merely providing a suitable 5 point of attachment for a lifting cable.

It is one object of the invention to provide an anchor of the character indicated that will have a positive seat in the marble or stone without utilizing any expansion 10 mechanism such as is ordinarily used.

It is another object of the invention to provide an anchor of the character indicated that is exceedingly economical to manufacture, and one that may be seated in the 15 stone or marble with a minimum amount of labor.

In the drawing:—

Figure 1 is a plan view of a device embodying my invention in position in a 20 marble slab.

Figure 2 is a sectional view through the slab showing the device in elevation.

Figure 3 is a sectional view through a slab showing another embodiment of my invention.

Figure 4 is a sectional view through a slab showing still another embodiment of my invention.

Figure 5 is a plan view of a portion of a slab showing the method of forming the anchor seat.

Referring more particularly to the drawing, I show at 1 a portion of a slab of marble or stone or any other similar material. In 35 preparing this slab for the anchor two round holes are drilled therein at right angles to the plane of the surface of the slab and at diverging angles from a center line 2 as indicated at 3—3, and the partition 4 dividing the holes is then broken away. In the 40 forms of the invention shown in Figures 1, 2 and 3 the corners 5 are also broken away to permit the insertion of the larger element of the anchor, in the resulting cavity or 45 recess 6.

At 7 I show a solid pyramidal element, rectangular in cross-section at right angles to its longer axis, its greatest cross-sectional area being slightly less than that of the mouth of the recess 6 as clearly shown in 50 Figure 1. The smaller upper end of this element is tapped at 8 to receive a bolt as 9.

At 10—10 are a pair of semi-cylindrical elements, the diameter of each element being substantially the same as the thickness 55 of the element 7 and its curved surface be-

ing such as to snugly fit one of the end walls of the recess 6.

In using this form of my invention the element 7 is first dropped into the recess 6 large end down, and then the two semi-cylindrical elements 10—10 are dropped in, one on each end of element 7. If a plate such as 11 is to be secured to the slab it is now placed in position and the bolt 9 inserted therethrough and into engagement with the tapped element 7. By tightening up the bolt the element 7 is drawn upwardly into positive contact with the elements 10—10. By this construction and arrangement of parts the engagement of the anchor with the slab is positive. There is no opportunity for any of the parts to slip as is the case when an ordinary expansion bolt is used.

In the embodiment shown in Figure 3 I show a short element 12 having the same general shape as the element 7 described but shorter and so formed that it may be a casting or it may be stamped out of sheet metal. With this element 12 are used the two semi-cylindrical parts 13—13 and a plate or washer 16 set upon their upper ends. A bolt 14 passes through the part 15 to be mounted on the slab and through the washer 16 and is screwed into the part 12. When the bolt is tightened up it draws the part 12 upwardly into solid contact with the parts 13—13 and firmly binds the part 15 in position.

In the embodiment shown in Figure 4, I show an element 17 similar in form to element 12 hereinbefore described but having two of its diametrically opposite corners rounded off as shown at 18 and 19. By 95 rounding these corners off in this manner a much smaller recess 6 may be provided, because the part may be dropped into the recess endwise and then turned through the position indicated in dotted lines at 20 to 100 the position 21, whereupon the bolt 22 may be threaded into it. The upward or outward pull on the bolt 22 will of course draw the element 17 into solid contact with the end walls of the recess. In this form no semi-cylindrical parts such as 13—13 are required because the length of the element 17 is greater than the length of the mouth of the recess 6 and therefore cannot be pulled therethrough without being turned endwise. 105 This embodiment permits the use of a much smaller recess and a single cast or stamped 110

element 17 in addition to a bolt for engagement therewith. It may also be readily seen that this form of anchor may be easily aligned with any fixed opening within a limited radius by the use of shims at either end.

An anchor constructed after the manner disclosed is not only positive in its engagement with the slab or block in which it is placed, but it becomes a permanent part thereof. It cannot become loose in the lapse of time, and therefore combines permanency with economy of manufacture, and ease of installation.

In the following claim the term "base part" is used to designate any element of stone, marble or other material provided with a socket for the reception of the anchor.

It is to be understood, of course, that while I have herein shown and described the pre-

ferred embodiments of my invention, changes in form, construction and method of application may be made within the scope of the appended claim.

I claim:

The combination with a base part having a socket formed therein, the said socket having inwardly diverging side walls, a key having a length less than the depth of said socket adapted to engage each side wall, a wedge shaped element engageable with the opposing surfaces of the lower ends of said keys, a washer mounted upon the upper ends of said keys, a supported element mounted upon said base and washer, and a bolt passing through said supported element and washer and engaging said wedge shaped element.
